US0D1093531S

(12) **United States Design Patent** (10) Patent No.: **US D1,093,531 S**
(45) Date of Patent: ** Sep. 16, 2025

(54) **INFLATABLE SLIDE**

(71) Applicant: **Zhiying Li**, Guangdong (CN)

(72) Inventor: **Zhiying Li**, Guangdong (CN)

(**) Term: **15 Years**

(21) Appl. No.: **29/999,790**

(22) Filed: **Apr. 16, 2025**

(51) LOC (15) Cl. **21-03**

(52) U.S. Cl.

USPC **D21/818**; D21/835

(58) **Field of Classification Search**

USPC D21/811, 814, 818-822, 835

CPC A63G 21/00-21/22; A63G 31/00; A63G 31/12

See application file for complete search history.

(57) **CLAIM**

The ornamental design for a inflatable slide as shown and described.

DESCRIPTION

FIG. 1 is a forward left perspective view of a inflatable slide, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are for the purposes of illustrating portions of the inflatable slide, which form no part of the claimed design.

1 Claim, 8 Drawing Sheets
